UNITED STATES PATENT OFFICE.

EDWARD THOMAS PEARSON, OF WASHINGTON, DISTRICT OF COLUMBIA.

FILE-HOLDER AND CASE.

SPECIFICATION forming part of Letters Patent No. 296,611, dated April 8, 1884.

Application filed January 24, 1884. (No model.)

To all whom it may concern:

Be it known that I, EDWARD T. PEARSON, a subject of the Queen of Great Britain, residing at Washington, in the District of Columbia, have invented certain new and useful Improvements in File-Holders and Cases, of which the following is a specification, reference being had therein to the accompanying drawings.

My invention has relation to file-holders and cases; and the object is to provide a simple and durable file-holder and case for the use of the various departments of the Government, as well as professional and private parties, for the preservation of papers, documents, and the like; and the novelty consists in the construction of the same, as will be hereinafter more fully described, and particularly pointed out in the claims.

In the accompanying drawings the same letters of reference indicate the same or like parts of the invention.

Figure 1 is a perspective view of the file-holder removed from the case and in position for examination. Fig. 2 is a perspective elevation of the standard detached from the holder. Fig. 3 is a sectional elevation of the case with the file-holder in its closed position, and Fig. 4 a similar view with the holder drawn out and suspended in position for examination.

A is the base of the holder, and B the front.

C are the sides, and each is provided with a hook, c, formed integral with the side and extending through the base A. These sides C are secured to the front and base by screws in the usual manner.

D are recesses in the sides C, and extend nearly the whole length of said sides.

E is the standard provided with follower F, and having the forwardly-projecting arms G G, extending under the sides C, so as to slide freely in the recesses D D, and the extremities of said arms have guards e e, which prevent any undue lateral play of said standard.

H is the base or fulcrum of the standard, and when it is in position it rests on the inner face of the front B, with the arms G G in the recesses D D, as shown in Fig. 1. If a pressure be brought to bear on the face of the follower F, said pressure is communicated to the standard E at I, which presses the fulcrum-point H against the face of the front B and throws the arms G G upward in the recesses, so as to bind firmly against the lower ends of

the sides, which rigidly locks the standard in position.

To release the standard, the first two fingers of the hand are inserted between the standard and the follower, near its base, and a slight pull backward given, while at the same time the thumb presses the top I forward. This motion raises the fulcrum H from the front and releases the standard, and it may then be drawn back to the end of the recesses D D.

65

To lock the standard, the files or papers are placed in the holder and the standard pushed forward until the follower compresses the files, and the hand is then removed. The expansion of the files upon the follower is communicated to the upper part, I, of the standard, which presses its fulcrum down and throws the arms up, thus firmly locking it in position.

K is the file-holder case, preferably constructed of wood, and each pigeon-hole is provided with a pair of metallic rails, N, having flange N' and a boss, n, through which passes a rod, n'. The base of the holder slides in upon these rails, as shown in Fig. 3, and when the holder is drawn out the hooks c engage with the rod n', which allows the holder to tilt forward and remain in an upright suspended position on the front of the case, as fully shown in Fig. 4.

85

To remove the holder entirely from the case, it is raised an inch or so vertically, which releases the hook c from the rod n', and it may then be detached from the case.

Having thus described my invention, what I claim as new and useful, and desire to secure by Letters Patent of the United States, is—

1. In a file-holder, the sides C, having recessed slots D, in combination with the standard E, having forwardly and laterally projecting arms G G, as and for the purposes set forth.

95

2. The combination, with the wooden case K, provided with metallic rails N, having bosses n and the cross-rod n', of the holder consisting of the base A, front B, and sides C, having hooks c c, and standard E, having follower F, as and for the purposes set forth.

100

In testimony whereof I affix my signature in presence of two witnesses.

EDWARD THOMAS PEARSON.

Witnesses:

A. S. TAYLOR,
H. J. ENNIS.
